[57] CLAIM

The ornamental design for paint bucket screen, as shown and described.

DESCRIPTION

FIG. 1 is a front elevational view for a paint bucket screen showing our new design.

FIG. 2 is a rear elevational view.

FIG. 3 is a left side elevational view.

FIG. 4 is a right side elevational view.

FIG. 5 is a top plan view.

FIG. 6 is a bottom plan view; and,

FIG. 7 is a sectional view.

The cross hatching shading in all the figures is partially shown for convenience of illustration, it being understood that it is uniformly continued over the surface on which it appears.
